DESIGN FOR A TAPE-DISPENSING MACHINE

Herman H. Hillmer, Omaha, Nebr., assignor to Better Packages Incorporated, Shelton, Conn., a corporation of New York

Application June 13, 1946, Serial No. 130,680

Term of patent 14 years

(Cl. D74—1)

To all whom it may concern:

Be it known that I, Herman H. Hillmer, a citizen of the United States, residing in Omaha, in the county of Douglas and State of Nebraska, have invented a new, original, and ornamental Design for a Tape-Dispensing Machine, of which the following is a specification, reference being had to the accompanying drawing, forming part thereof, in which

Fig. 1 is a side elevational view of a tape-dispensing machine showing my new design;

Fig. 2 is a similar view taken from the opposite side thereof;

Fig. 3 is a front elevational view; and

Fig. 4 is a top plan view.

I claim:

The ornamental design for a tape-dispensing machine, substantially as shown.

HERMAN H. HILLMER.
